ARTIFICIAL EYELASH CONTAINER

Douglas S. Rhee, Long Island City, N.Y., assignor to Rheemont Enterprises, Inc., Brooklyn, N.Y., a corporation of New York

Filed Oct. 19, 1965, Ser. No. 87,604

Term of patent 3½ years

(Cl. D9—223)

FIG. 1 is an exploded perspective view of an artificial eyelash container embodying my new design;

FIG. 2 is a top plan view thereof, the lid being removed for convenience of illustration;

FIG. 3 is a side elevational view thereof, the opposite side being identical;

FIG. 4 is a bottom plan view thereof;

FIG. 5 is an end elevational view thereof, the opposite end being identical; and

FIG. 6 is a side elevational view showing the cover in its normal position on the base.

I claim:

The ornamental design for an artificial eyelash container, as shown and described.
